GIRDLE

Catherine P. Prochaska, Fairfield, Conn., assignor to The Warner Brothers Company, Bridgeport, Conn., a corporation of Connecticut

Application July 15, 1954, Serial No. 31,430

Term of patent 14 years

(Cl. D20—2)

To all whom it may concern:

Be it known that I, Catherine P. Prochaska, a citizen of the United States, residing at Fairfield, Connecticut, have invented a new, original, and ornamental Design for Girdle, of which the following is a specification, reference being had to the accompanying drawings, forming a part hereof, in which:

Fig. 1 is a front elevational view of a girdle showing my new design.

Fig. 2 is a rear elevational view of said girdle.

I claim:

The ornamental design for girdle, as shown.
